SLIDE-HOLDING TRAY FOR PROJECTION MACHINES

William N. Geiger, Glendale, Calif.

Application July 27, 1956, Serial No. 42,430

Term of patent 14 years

(Cl. D61—1)

Fig. 1 is a perspective view of a slide-holding tray for projection machines, showing my new design.

Fig. 2 is a perspective view thereof, as seen from the opposite side.

Fig. 3, to a reduced scale, is a fragmentary vertical sectional view as taken on the line 3—3 of Fig. 2.

I claim:

The ornamental design for a slide-holding tray for projection machines, substantially as shown.
